UNITED STATES PATENT OFFICE

AUDLEY E. HARNSBERGER, OF CHICAGO, ILLINOIS, ASSIGNOR TO THE PURE OIL COMPANY, OF CHICAGO, ILLINOIS, A CORPORATION OF OHIO

VACUUM SYSTEM OF OIL CONVERSION

Application filed May 31, 1928. Serial No. 281,785.

This invention relates to improvements in the art of manufacturing gasoline like hydrocarbons, and has particular reference to a system of oil conversion wherein the oils are maintained substantially in a state of vapor while passing through a heated cracking or reaction zone, and one of the outstanding features of the present invention resides in a vapor phase method of oil conversion wherein the oils while undergoing conversion are maintained under subatmospheric pressure conditions.

It is another object of the invention to provide a jet condenser in communicating relationship with the outlet of the converter and by means of which condenser oil may be brought into intimate relationship with the cracked vapors as the latter emerge from the converter outlet in order that: First, the conversion reactions in the cracked vapors may be instantly arrested by reducing the temperature of such vapors below reaction temperatures, and, second, to produce subatmospheric pressure conditions in the converter proper so that the oil or oil vapor while undergoing conversion is maintained either in part or all together under subatmospheric pressures.

There are certain advantages resulting in cracking oil or oil vapors under sub-atmospheric pressures as compared with the customary methods of converting oil under high super-atmospheric pressures. For example, there is obtained (1) a reduction in fixed gas formation per unit quantity of gasoline like hydrocarbons produced, (2) reduction in time the vapors are exposed to cracking temperatures by increased velocity of travel of the vapors through the cracking zone, (3) improved control in the temperature of the vapors leaving the converter and other factors affecting the molecular decomposition of oil by vapor phase methods of conversion.

Again, it is the purpose of this invention to overcome some of the difficulties in connection with sub-atmospheric vapor phase systems of cracking. One of the chief of these difficulties is the removal of the so-called permanent gas from the system and condensation of the lighter hydrocarbons which fall

into the gasoline series under normal or atmospheric pressure. These difficulties are overcome entirely by using the hurling liquid type of jet condenser in which the stored energy in a liquid such as oil is utilized to increase the pressure of vapors passing through the condenser from sub-atmospheric to an above atmospheric condition. Once these vapors are at a pressure above atmospheric the condensation of the gasoline fractions and the removal of the permanent gas presents no difficulty, since it eliminates large vacuum pumps and similar equipment.

In the apparatus described it is desirable that on the outlet side of the jet condenser a temperature of from 400° F. to 600° F. be maintained so that the gasoline produced as a result of the cracking reaction may be easily recovered by the well-known principles of fractional condensation. The degree of vacuum carried on the inlet side of the jet condenser will depend largely on the pressure and quantity of hurling liquid used therein. This hurling liquid may be of different temperatures ranging from below 100° F. up to 75 as high as 400° F., thus permitting of a wide variance in the weight of hurling liquid used and consequent control of the degree of vacuum carried on the converters. Thus with converter tubes of a given cross sectional area, 80 the velocity of vapors traveling therein can be greatly varied by increasing the vacuum on the outlet side and in this manner control of the time which the vapors are exposed to high temperatures can be varied to suit the 85 type of charging stock.

For a further understanding of the invention reference is to be had to the following description and the accompanying drawings wherein:

Figure 1 is a diagrammatic view of apparatus which may be used in carrying out the present invention.

Figure 2 is an enlarged sectional view taken through the jet condenser which operates as 95 a heat transfer agent at the end of the converting zone.

Figures 3, 4 and 5 are detail views showing modified types of converter tubes.

Referring more particularly to the details 100

of the process the numeral 1 designates a pipe 5 still or vaporizer, which is formed to include a setting 2, which is divided internally by a bridge wall 3 into combustion and tube heating chambers. Oil burners or the like are situated in the combustion chamber and operate to develop heat which is carried to a bank of tubes 4 arranged in the heating chamber. Oil under process of treatment 10 such for example, as a gas oil fraction, enters the tubes 4 by way of the pipe line 5, and is discharged from the tubes 4, after heat treatment, by way of the outlet line 6. In one form of the invention it is customary to heat 15 the oil passing through the vaporizer until it attains a temperature bordering on molecular decomposition such, for example, as from 700 to 750° F. This temperature reduces the oil to a very large extent to a state 20 of vapor, and the combined oil and oil vapors are then transferred, under circulation pressures merely, to an evaporator 7 which is connected with the discharge end of the outlet line 6.

25 The evaporator is of customary form and includes an enlarged base portion adapted to receive the unvaporized or liquid fractions of the oil discharged from the vaporizer. It is desired that these heavy fractions, which 30 do not vaporize at temperatures of from 700 to 750° F. shall be independently collected and removed from the system. This is efficiently done by the evaporator 7, which functions to collect such heavier fractions in the 35 base portion thereof, and to permit such heavy fractions to be removed by way of a discharge line 8 as fuel oil. The top of the evaporator may include a tower which is provided with suitable baffles, arranged to 40 intercept the flow of the oil vapors and to knock down entering liquid.

The vapors leaving the top of the evaporator pass by way of a pipe line 9 to a liquid trap or separator 10. This trap 45 includes a plurality of vertically arranged relatively spaced and staggered baffles 11 which act to supplement the action of the evaporator 7 in that the separator serves to insure substantially the complete removal 50 of all entering liquid from the vapors, before such vapors enter the converter 12.

The converter 12 comprises a setting 13 formed to include a transversely extending bridge wall 14 which separates the converter 55 into radiant and convected heat chambers 15 and 16 respectively. Communicating with the pipe line 9 on the outlet side of the separator 10 is a tubular heating element 17 formed from materials possessing good heat 60 conductivity but capable of withstanding relatively high furnace temperatures without undue deterioration or destruction. The inlet portion of the heating element 17 is situated in the radiant heat chamber 15 in order 65 that the temperature of the oil vapors pass-

ing through said heating elements may be rapidly raised upon entering the converter from approximately 700 to 750° F. to a temperature in excess of 1000° F. In the operation of the system it has been found that by 70 abruptly and substantially instantaneously elevating the vapor temperatures within the limits specified very little or no free carbon precipitation or accumulation takes place in the inlet portions of the converter tubes. If 75 desired, a relatively small percentage of steam may be admitted into vapor lines between the vaporizer and the converter. Experience has demonstrated that a small quantity of such steam is helpful in minimizing 80 carbon formation in the converter and is believed to assist conversion reactions in the converter tubes 17.

The oil and steam vapors flow at relatively 85 high velocities through the heated tubular element 17 during which time the vapors are maintained preferably at temperatures in excess of 1000° F. and for a period of time not in excess of two seconds.

When the vapors are discharged from the converter it is necessary to effect an abrupt 90 and substantially instantaneous drop in the temperature of the vapors from, for example, 1000° F. to 600° F. To accomplish this there is employed, in the present instance, a unit known as a jet condenser or a hurling liquid type booster. As shown in figure 2 95 this unit comprises a casing 18, which is formed to include a flanged head 19 suitably secured to the outlet side of the converter elements 17. Within the central portion of the head 19 there is situated a vertically disposed injection nozzle 20, which is connected with a fresh oil supply line 21. This line leads from a source of fresh oil supply such 100 as a tank 22, and the line 21 is provided with a pump 23 between the tank 22 and the nozzle 20, so that the fresh oil may be discharged at high velocity in jet formation. Due to the location of the nozzle 20 the oil released therefrom is brought into very intimate contact with the highly heated vapors issuing from the converter while both the cooling oil and the heated vapors are moving at the same velocity. Immediately below the nozzle 20 the casing 18 includes a restricted 105 throat 24, which terminates in a flaring expansion chamber 25.

It has been noted that in the operation of 110 vapor phase systems of this kind that best operation is obtainable, that is maximum motor fuel yields with but minimum formation of fixed gas, when the vapors pass through the converter elements under the lowest pressures. Heretofore these pressures 115 have always been super-atmospheric but by the provision of the jet condenser unit, above described, the system operates ordinarily with the converter under sub-atmospheric pressures. It will be observed that the liquid 120 125 130

or fresh oil introduced into the jet condenser by way of the line 21, serves to arrest and substantially instantly check conversion of cracking reactions on the part of the oil vapors leaving the converter, by sharply dropping the temperatures of such vapors from 1000 to 600° F. or lower. This has been obtained by previous types of coolers, but in the present invention not only is the oil vapor cooled but in addition conditions are created by which sub-atmospheric pressures obtain within the heating element 17 of the converter.

The oils leaving the outlet side of the jet condenser unit at a super-atmospheric pressure pass into the bottom of a fractionating tower 26. The volatile fractions of the oils entering the tower, or those fractions which remain in a state of vapor at temperatures below 600° F. pass upwardly through the tower and are suitably condensed, collected, treated and stored for use as a motor spirit. The fractions which are not vapors at temperatures below 600° F. accumulate as a liquid in the bottom of the tower 26 and by means of a pump 27 may be forced through the inlet line 5 back through the system for recirculation with a certain proportion of the fresh oil. In the operation of the system a greater amount of fresh oil is forced through the jet condenser than is actually needed to replenish the fresh oil demands of the system as the finished motor spirit is drawn off. As a result of this condition there accumulates from time to time an excess quantity of liquid oil in the base of the tower 26. Through suitable automatic valve mechanism, when the liquid level reaches a certain point in the bottom of the tower 26 the excess liquid is returned to the fresh oil tank 22 and may then be re-introduced into the system by way of the jet condenser, as previously explained.

The fresh oil or liquid introduced by way of the jet condenser unit into the system possesses ordinarily an atmospheric temperature but which may of course be higher, and in its jet form, when it issues from the nozzle 20, the oil effectively serves to cool the heated converted vapors by effecting the temperature drop specified in approximately one-fifth part of a second. It has been found that by preventing a long drawn out cooling of the oil vapors, when they leave the converter, as is secured by means of ordinary vapor condensers, practically all free carbon, deposition or formation in this portion of the system is eliminated. The operation must be substantially instantaneous to obtain the greatest degree of success, and the present invention secures this result to a remarkable degree by reason of the peculiar formation of the interior of the jet condenser unit and the fact that construction provides for positive contact of all parts of the vapor and liquid

streams. In addition the unit provides for producing the sub-atmospheric pressures in the converter, which provides for higher velocity of oil vapor travelling through the high temperature zone of the converter and in this manner reduces the formation of fixed gases or non-condensables. Heretofore, it has been a difficulty in sub-atmospheric systems to separate the so-called permanent gases of the system from the lighter hydrocarbons which fall into the gasoline series under normal or atmospheric pressures. This difficulty has been overcome entirely by using the hurling liquid type of jet condenser, as shown, in which the stored energy in a liquid, such as oil, is utilized to increase the pressure of vapors passing through the condenser from sub-atmospheric to super-atmospheric conditions. It will be understood that when these vapors are again at a pressure above atmospheric the condensation of the gasoline fractions and the removal of the permanent gas presents no difficulty and involves ordinary operations with standard equipment.

In the apparatus described it is desirable that on the outlet side of the condenser a temperature of from 400° F. to 600° F. be maintained so that gasoline produced as a result of the cracking reactions may be easily recovered by the well known principles of fractional condensation. The degree of vacuum carried on the inlet side of the jet condenser depends largely on the pressure and quantity of hurling liquid used therein. This liquid may be of different temperatures ranging from below 100° F. up to as high as 400° F., thus permitting a wide variance in the weight of the hurling liquid used and consequent control of the degree of vacuum carried on the converters. Thus with the converter tubes of a given cross sectional area, the velocity of vapors travelling therein can be greatly varied by increasing the vacuum on the outlet side and in this manner control of the time to which the vapors are exposed to high temperatures can be varied to best conform with the type of charging stock employed. Additional control can be secured by providing the tubular converter elements with tapering cores of a catalytic material such as ferrous oxide mixed with concrete, or if desired the converter tubes themselves may be of conical or tapering form. In this manner the effective area for vapor travel through the converter elements may be regulated at will to secure high or low velocities of oil travel with a substantially constant vacuum.

The present invention therefore provides a vapor phase system of cracking oil wherein an improved method is provided for instantly arresting conversion reactions in the highly heated oil vapors discharged from the cracking zone. This is accomplished primarily by the employment of the cold oil in-

jector 18 which functions to provide for intimate mixing of the cracked vapors with the fresh liquid oil of lower temperature, whereby a rapid exchange of heat takes place between the oil vapors and the liquid oil to arrest abruptly conversion reactions in the discharged vapors. Due to its location in relation to the vapor outlet of the converter the jet cooler tends to produce a suction or partial vacuum in the vapor passages of the converter so that lower furnace temperatures within the converter may be utilized with the consequent reduction in the formation of fixed gases.

15 What is claimed is:

1. The process of converting high boiling point hydrocarbons into those of lower boiling point, which comprises heating the oil initially introduced into the process to a temperature sufficiently high to convert the same from its normally liquid to a substantially dry vaporous state, then subjecting the vapors to temperatures in excess of approximately 1,000° F., maintaining the vapors at such latter temperature for a period of time sufficient to effect desired conversion reactions, and then forcing the vapors through a restricted conduit together with a liquid jet of cooler oil for the purpose of abruptly lowering the temperature of the vapors to a point not in excess of 600° F. and to produce sub-atmospheric pressures in the conversion zone.

2. The process of treating hydrocarbon oil, which comprises continuously passing a confined stream of vaporized oil through a heated conversion zone, abruptly arresting conversion reactions of the vapors leaving said conversion zone by passing the vapors through a restricted passage and while in such passage bringing the vapors into intimate contact with a confined and positively advanced moving stream of liquid oil having a temperature materially lower than that of said vapors, the merging of said vapors and moving stream of liquid oil in said restricted passage serving to provide for the maintenance of subatmospheric pressures in the vapor passages of said conversion zone.

50 3. The process of treating hydrocarbon oil, which comprises converting the oil in the vapor phase, and immediately upon completing the desired conversion of the oil in the vapor phase abruptly and substantially instantly arresting the conversion reactions by bringing the highly heated vapors into physical contact with a forced moving stream of relatively cool liquid oil, said liquid oil and vapors being continuously passed at the time of merger through a passage of restricted cross-section whereby to produce sub-atmospheric pressures in the zone of vapor conversion and super-atmospheric pressures in the zone immediately beyond said restricted passage.

4. The process of treating hydrocarbon oil, which comprises passing a constantly moving stream of oil vapor through a heated conversion zone and therein subjecting the oil vapor to temperatures in excess of 1,000° F., immediately upon completing the desired conversion of the oil in the vapor phase abruptly and substantially instantly arresting the conversion reactions by bringing the heated vapors into intimate contact with a forced moving stream of liquid oil of relatively low temperature, said liquid oil and vapors being merged in stream-like formation in a single passage of restricted cross-sectional area whereby the movement of said confined stream of liquid oil and vapor serves to produce sub-atmospheric pressures in the outlet portion of said conversion zone and an immediate reduction in the temperature of the vapors leaving the conversion zone to non-reacting temperatures not in excess of 600° F.

5. The process of treating hydrocarbon oil which comprises passing a continuous moving stream of oil vapor through an elongated conversion zone of restricted cross-sectional area and heating the vapors during their passage through said zone to a temperature in excess of 1,000° F., immediately upon completing the desired conversion of the oil in the vapor phase abruptly and substantially instantly arresting the conversion reactions by bringing the moving stream of highly heated vapors into physical contact with a forced moving stream of liquid oil of relatively low temperature, said liquid and vapor oil streams being merged in a confined passage of restricted cross-sectional area whereby to produce sub-atmospheric pressures in the vapor passages of said conversion zone and super-atmospheric pressures in the zones immediately following the restricted passage wherein said liquid and vapor oil streams are merged, and then continuously passing the combined liquid and vapor oil streams at a non-reacting temperature not in excess of 600° F. into a fractionating zone and therein fractionating the liquid and vapor oil stream.

In testimony whereof I affix my signature.
